MARTIN KALLMANN, OF BERLIN, GERMANY; PAULA KALLMANN, OF BERLIN, GERMANY, ADMINISTRATRIX OF SAID MARTIN KALLMANN, DECEASED.

SWITCHING DEVICE FOR ELECTRIC CIRCUITS.

1,085,266.

Specification of Letters Patent.

Patented Jan. 27, 1914.

Application filed June 26, 1906. Serial No. 323,538.

To all whom it may concern:

Be it known that I, Dr. MARTIN KALLMANN, a subject of the Emperor of Germany, residing at Kurfürstendamm 40/41, 5 Berlin, W., Germany, have invented certain new and useful Improvements in Switching Devices for Electric Circuits; and I do hereby declare the following to be a full, clear, and exact description of the invention, such 10 as will enable others skilled in the art to which it appertains to make and use the same.

My invention relates to devices in cut-outs, reversing-switches, automatic contact-breakers, cell-switches, and the like, and has for its object the prevention of violent break-sparks and flashing at the contacts, though it can also be employed with advantage to prevent extra-currents on the interruption 20 of circuits with high self induction. This is attained by inserting in the circuit at the contact point or place of break or reversal a resistance of high temperature coefficient, especially iron, which on passage of current 25 increases, on being heated to red-heat, many times in resistance and thus weakens the current to such an extent that the final interruption of the circuit takes place almost without sparking and any extra-currents remain but small.

Figures 1 and 2 show the changes in current strength in a circuit during the operation of cutting off the current through a self-acting resistance as in my improved 35 switch. Fig. 3 shows a single pole switch and the connections between the supplementary switch and the self-acting resistances. Fig. 4 shows a bi-polar switch with the accompanying resistance and supplementary 40 switch. Fig. 5 shows means for controlling the supplementary switch by means of which the current is short circuited through the resistance. Fig. 6, shows a device in which an 45 excess of current causes the breaking of the main circuit and the opening of a bypass through the special form of resistance which I provide. Fig. 7 shows another device for 50 accomplishing the same result. Fig. 8 shows the switch as applied to an accumulator.

The resistance, in order to insure as small a capacity for heat as possible, may be made of very thin iron wire which for the purpose of preventing oxidation may, like incandescent lamp filaments, be inclosed in a 55 vacuum, for instance a glass box or better in

an atmosphere of hydrogen or other indifferent gas. If for example, the resistance is calculated for a current of 2 amperes, the voltage at its ends increases rapidly with this current strength by reason of the heat- 60 ing, while the current remains almost constant, provided that the iron resistance forms the main portion of the circuit resistance, for example if the increase is from 10 to 50 volts. It is only when a higher temperature 65 is reached that the essential increase in resistance ceases and the current-strength then increases further. In an iron wire for instance, 0.36 mm. thick there is 2 volts fall of potential for $\frac{1}{2}$ ampere current, that is 4 70 ohms resistance; for 1 ampere and moderate heating, correspondingly 5 volts and 5 ohms; for 2 amperes and dark red heat, correspondingly 22 volts and 11 ohms; for 2.2 amperes and medium red heat 50 volts and 23 ohms; 75 for 2.3 amperes and bright red heat 75 volts and about 33 ohms. Thus if in a circuit of 220 volts there is a load of 20 amperes corresponding to 11 ohms resistance of the lamps or the like, and if this load were cut 80 out direct, there would be very considerable sparking caused. If however, there is introduced at the place of break, in suitable manner, a reducing resistance, which in working is short-circuited, then on opening the switch 85 the current at the first moment, (if this resistance when cold is about 4 ohms,) will be

$$\frac{220}{11+4} = 14.7 \text{ amperes.}$$

90

The break spark with this small change of current (from 20 to 14.7) is naturally but trifling. Within a few seconds the thin iron wire will now become incandescent and increase in resistance to for instance, 33 ohms. 95 The current-strength of the circuit then sinks to

$$\frac{220}{11+33} = 5 \text{ amperes.}$$

100

and these remaining 5 amperes can likewise be interrupted without any considerable sparking. The case is similar on direct short circuiting taking place, where for instance, some $5\frac{1}{2}$ amperes current only have still to 105 be interrupted. This process can be used without difficulty by simple bridging of the place of break either by a single or multiple-pole switch, two breaks or if necessary more stages, being thus employed. In the latter 110

case there are several sections of the reducing resistance to be cut out in stages.

Any form of switch, such as lever, rotary or reversing switches with several contacts may be used. If extremely thin iron wires of say 1/40 mm. thickness be used the reducing resistance will under certain circumstances be heated to red heat in less than a second, so that a switch may be employed in which the main and shunt circuits are opened in rapid succession.

The use of the reducing resistance is particularly important for automatically opening the circuit. This automatic operation may be applied either only for the shunt switch, while the main switch is opened by hand, or the entire switching operation may be effected wholly automatically. In the first case, as long as the main switch is closed (preferably positively), the shunt switch is also closed, and the reducing resistance thus short circuited. As soon as the main switch is opened the reducing resistance is cut into the place of break and the working current will flow through it. The current now falls again, as already explained, within a few seconds, by reason of the heating of the reducing resistance, and when it has reached a suitably small value, for example in the above case 5 amperes, an electromagnet, which is traversed either wholly or partly by the main current, releases its armature, which now interrupts the remaining current by cutting out the shunt (reducing resistance). Thus the electromagnet armature falls of itself shortly after opening of the main switch. This can naturally also be done gradually in several stages if necessary by means of several electromagnets or electromagnetic armatures. For the circuit however, the danger of too great current-strength is removed immediately on opening of the main switch, since the rapidly increasing reducing resistance quickly diminishes the intensity. With entirely automatic switching the matter is similar. The reducing resistance is combined with an automatic device of suitable construction. When the current is excessive the main contact is opened by the operation of a solenoid and the iron resistance is interposed in the path of the current, causing the latter to fall, and the circuit is then fully opened by the operation of the supplementary switch. The first electromagnet would thus soon effect the first interruption in well known manner on too strong a current passing, while the second electromagnet would release its armature on a sufficiently weak current flowing, thus operating similarly to a "zero automatic switch" or a minimum-current cut-out. Or the maximum and minimum switching may be done simply by a single electromagnet which first with too strong a current attracts an armature, thus cutting in the reducing

resistance, and then when the current is sufficiently weakened again, releases the armature, so that the entire circuit is broken. In this case suitable double lever switches and the like are necessary for the contacts (a main and a secondary contact).

The combination of the electro-magnet with one or more armatures may be varied as desired corresponding to the construction of the automatic device, the modern electromagnets of pot or other shape, boxed in as far as possible, being preferably employed.

In the same manner distance switches, reversing-switches, double pole switching devices, etc., with the aid of reducers enable practically sparkless break. Similarly circuits with high self-induction (for instance magnetic fields of dynamos or motors) can be broken in this manner without strong extra currents being caused. The action of the reducer when applied to cell-switches of accumulators is similar. Here the iron wire reducer is inserted in well known manner between the two-part cell-switch crank, or the sliding contact, instead of the usual constant resistance. As soon as the contact bridges a cell, a strong current will flow through the iron resistance and the value of the latter will rapidly increase, so that the discharging current of the cell is quickly decreased. The advantage here attained is that both the initial spark on closing the cell on the initially very small (cold) resistance, and the subsequent spark on cessation of closing, by reason of the then very weak discharging current (since the resistance is in highly incandescent state) are but very small, smaller than when for instance nickel-constant resistance, as usually employed for bridging in cell switch contacts, is used. This is of special importance when two cells have to be connected to each contact, for instance with 440 volt installations.

One form of device for carrying out the above described invention is illustrated diagrammatically in Fig. 3.

When opening the switch 1 the secondary switch 2 is still closed, so that the whole current to be consumed, which undergoes a proportionately small weakening in consequence of the still cold reduction-resistance 3, flows through the lamps 4, or the like, and the said reduction-resistance. After a few seconds, the resistance 3 has become red-hot, and has consequently been greatly increased. Now the switch 2 can be opened without much sparking, as the current has in the meantime been reduced automatically to a small fraction of its initial value. Serious sparking is thus avoided, on opening the main switch and also on opening the supplementary switch. On closing the circuit, the switch 2, or the switch 1, may at will be closed first, or both may be closed at the same time. On opening them, the secondary

switch of the reduction-resistance must always follow the main switch, for this secondary switch causes the interruption of the rest of the current.

5 Fig. 4 represents the system applied to a bipolar switch. Only one reduction-resistance is needed, but it is better to use two resistances, shown at 3, which are connected both to a branch lead, and the two switches 10 are then made bipolar in the usual way for reducing the break-spark. The working will, at once be seen from the preceding description. The circuit containing an inductive load 5 is in the first place broken by 15 means of the switch 1 and then finally by the switch 2. If very thin iron spirals of an exceedingly small heating capacity are used, the reduction-resistance, which is considerably overloaded by high currents to be 20 broken, or extra currents, becomes red-hot in some cases in less than one second, so that a single quick break switch may be used instead of two switches.

The opening of the secondary circuit can 25 also be effected automatically in a very simple manner, especially by using reduction-resistances which do not become incandescent instantaneously, but only after a few seconds, as illustrated in Fig. 5. Here the 30 current flows from the positive pole in the first place through a coil 10 of a small electromagnet 11, passes over the pivot 12 into the knife of the lever-switch 1, and would, if the circuit were closed, flow in the direction of the arrow over contact 14 into the outer circuit, and from here to the negative pole. If resistance is intercalated, the electromagnet 11 is excited and attracts its armature 15, against the action of the 35 spring 17, so that the secondary contact 19, 20, and through the same reduction resistance 3 are likewise connected, but in consequence of the short-circuiting by the main lever only a weak current flows through 40 them. During the switching off of the lamps or motors, the armature 15 would keep the contact 19, 20 closed for an adjusting screw 21 of the main lever insures the mechanical closing of the secondary contact, as long as the main lever is closed. If 45 the main lever switch 1 is opened and the contact broken at 14, the whole current then flows over the armature 15 of the electromagnet through 19 and 20, and the reduction-resistance 3, and from here over the outer circuit to the minus pole. The break-spark at the main contact 14 is only small on account of the by-path over the reduction-resistance, which offers only a small 50 resistance. After the interruption at 14, the armature 15 of the electromagnet is still held attracted by the electromagnet 11, as a strong current still flows through the windings 10. During the increased heating of 55 the reduction-resistance this current sinks,

however, within a few seconds to a fraction of the initial value, for instance, as shown by figures at the beginning, from about 15 to 5 amperes. Armature 15 is released by a spring 17, the contact 19, 20 is broken, and the circuit therefore fully opened. The secondary contact thus follows automatically the main contact, according to the load on the circuit, for if the strength of the current is very small, the armature 15, after 70 the opening of the main lever, drops at once off the electromagnet. The greater the load is the longer it takes until the current has been weakened sufficiently, whereupon the secondary circuit is likewise broken. By 75 closing the main switch 1, that is to say, by connecting the load, the contact 19, 20 is mechanically and automatically closed by means of the adjustable screw 21, so that the secondary circuit is always ready to 80 prevent the break-spark as long as the main switch is closed. This form may in the same manner also be adapted for bipolar switches. 85

Fig. 6 shows in a diagrammatic view the 90 same system for a self-acting switch, which, on a certain strength of current being reached, is intended to break a circuit, while Fig. 7 shows a practical form of construction of a self-acting switch. In Fig. 6 the 95 main contact 23, 24 is closed by a hooked lever 26, pivoted at 27. Contact 23 is connected with a spring 28. The path of the current over the reduction resistance 3 is broken by the contact 30 and 31. If the current in the releasing electromagnet 32 reaches a certain strength it attracts the armature 33, the lever 26 releases the contact 23 (pivoted at 34) from 24, the main contact is opened, and the current flows at the other 100 end of the two-armed lever, which at 35 contains an insulating-piece (the secondary contact 30, 31 being closed) and through the reduction-resistance 3, into the outer circuit. Here the current is only slightly reduced, 105 as the resistance 3 is still cold. In a very short time, however, for instance after 1 to 2 seconds, the resistance 3 becomes red-hot and in consequence the resistance of the circuit consisting of the lamps or other loads and the reduction-resistance, rises so high that the strength of the current in the electromagnet 32 sinks very considerably, for instance down to about the eighth part. In consequence of this the armature 33 drops off from the electromagnet under the influence of the spring 36, and thereby the whole circuit, inclusive of the reduction-resistance, is opened. 115 120

While in Fig. 6 the operation of the main lever is effected directly by an ordinary 125 electromagnet, the effect is produced in Fig. 7 in a different way, which allows of increasing the sensibility of the electromagnet. Here a special form of the electromagnet is shunted to a resistance 3, which may either 130

be formed after the usual manner of the main current resistances or of a resistance of a high temperature coefficient (for instance, iron) for increasing its sensibility. The current therefore flows, if the main switch 1 is closed, through this into the resistance 3 of the main circuit, and through the coil of the electromagnet 40, branching off from the same, into the outer circuit. If the current rises above a certain intensity, the iron core 41 is drawn into the coil of the electromagnet and releases the pawl 42 from the hook 43, whereby the main switch 1 standing under the action of the spring 44 and pivoted to 45 is released from the contact 46. Hereby the secondary contacts 47, 48 are also released by the adjusting screw 49 but remain still in contact, in consequence of being stopped by pawl 42' and hook 43'. This 20 keeps the secondary circuit closed through the reduction-resistance 3. Only when the intensity of the current, in consequence of the increased heating of 3, has sunk considerably, the iron core 41 drops down into the coil of the magnet 40 (the switch being mounted vertically) and strikes against pawl 42', which now releases the hook 43' of the lever 51, so that the latter under the influence of the spring 52, opens the secondary contact and completely breaks the circuit. According to the preceding calculations and examples, the opening of the main contact, as well as of the secondary contact, takes place without much sparking. 30 In the same manner, distance-switches, reversing-switches, double pole switching devices, etc., with the aid of reducers, produce a practically sparkless break. Similarly circuits with high self-induction (for instance magnetic fields of dyuamos or motors) 40 can be broken in this manner without strong extra currents being caused. The action of the reducer when applied to cell-switches of accumulators is similar, as shown in Fig. 8. 45 This is of special importance when, for example, two cells have to be connected to each contact, for instance with 440 volt installations. Here is intercalated instead of the usual constant resistance, which consists, as 50 a rule, of some windings of nickelene wire, or the like, a reduction-resistance 3 of iron, or the like, inclosed if necessary in a glass reservoir with hydrogen, between the crank of the cell-switch formed of two parts 60 and 61. The secondary contact 61 is insulated in the usual manner from the main contact and from the axle 62, or the current supply, by an insulated piece 65. In the 55 position shown in the drawing, the current would on moving the cell-switch flow from contact 63 over 60, 3, 61, 64. As the resistance 3 was thus far still cold, there does not take place during this movement of the 60 crank of the cell-switch any noticeable 65 weakening of the outer circuit, and there-

fore no reduction of the tension. Now the reduction-resistance 3 is heated until it becomes red-hot, and its ohmic value is thereby considerably increased and the rate of discharge of the cell or cells of the accumulator 70 is thereby lessened. Within one second the cell-switch may now be moved one cell farther on, in consequence of which the short-circuiting of the cell by the reduction-resistance ceases, without the formation of 75 any considerable break-spark, for the current to be broken is then only very weak. The same operation is repeated and the spark is very small on the succeeding contacts, in consequence of the described properties of 80 the reduction-resistance, which during its movement from cell to cell must have sufficient time to alternately cool down and get hot. In this way all other devices for the arresting of sparks can be entirely dispensed 85 with, while violent shocks of current during the movement of the cell-switches and reactions upon the tension of the system are reduced to a minimum, in consequence of the described properties. 90

Having thus described my invention, what I claim as new is:

1. The combination of an electric circuit, a switch therein, a second circuit, a supplementary switch and a resistance of a 95 high positive temperature coefficient in the second circuit and means whereby the latter switch is operated by the operation of the main switch in one direction, said supplementary switch being mechanically independent of the operation of the main switch in the other direction, means operated by an excess of current for opening the main switch, and a member also operated by such means for releasing the supplementary 100 switch.

2. The combination of an electric circuit, a switch therein, a second circuit, a supplementary switch therein, the latter being mechanically independent of the operation of the main switch during the opening operation, and electrical and mechanical means automatically operated for opening the supplementary switch at an interval after opening the main switch, such electrical means 115 including a conductor having a high positive temperature coefficient connected with the supplementary switch, the duration of said interval being determined by the effect of the current on such conductor. 120

3. In an electric switch the combination of a main switch, a supplementary switch adjacent thereto, mechanical means for closing the supplementary switch by the operation of the main switch, and electrical and 125 mechanical means for automatically opening the supplementary switch at an interval after the opening of the main switch, such electrical means including a conductor having a high positive temperature co-efficient 13

connected with the supplementary switch, the duration of said interval being determined by the effect of the current on such conductor.

- 5 4. In an electric switch the combination of a main switch, a supplementary switch adjacent thereto, adjustable mechanical means for closing the supplementary switch by the operation of the main switch, and
 10 electrical and mechanical means for automatically opening the supplementary switch at an interval after the opening of the main switch, such electrical means including a conductor having a high positive temperature co-efficient connected with the supplementary switch, the duration of said interval being determined by the effect of the current on such conductor.
- 15 5. The combination of a main electric circuit, a switch therein, a second circuit, a supplementary switch therein, a device on said main switch adapted to contact with said supplementary switch, a resistance of a high positive temperature coefficient in the second circuit, a solenoid, a pawl actuated by the armature thereof for releasing the main switch, and means engaging the supplementary switch and holding it closed until the current passing through the solenoid is
 20 sufficiently reduced to cause the armature to return to its normal position.
- 25 6. The combination of a main electric cir-

cuit, a switch therein, a second circuit, a supplementary switch therein, hooks on each of said switches, a solenoid, a pawl engaged 35 by the armature thereof when an excess of current is caused to pass through said solenoid, said pawl when operated releasing and opening the main switch, a second pawl simultaneously engaging the hook on the 40 supplementary switch and holding it closed while the excess of current is passing through the solenoid, means connected with the main switch adapted to contact with the supplementary switch and a resistance of a 45 high positive temperature coefficient in said second circuit.

7. The combination of an electric circuit, a switch therein, a second circuit, a supplementary switch therein, and a resistance 50 having a high positive temperature coefficient in the second circuit, the latter switch remaining closed after opening the main switch, and means for effecting in connection with the resistance the automatic release of the supplementary switch after an interval following the opening of the main switch.

In testimony whereof, I affix my signature, in presence of two witnesses.
